UNITED STATES PATENT OFFICE

116,927

DESIGN FOR A MOUNTING FOR FISHING REELS

Harold F. Wilson, Los Angeles, Calif.

Application January 5, 1939, Serial No. 82,167

Term of patent 14 years

To all whom it may concern:

Be it known that I, Harold F. Wilson, a citizen of the United States, residing at 4176 Garden Avenue, Los Angeles, county of Los Angeles, State of California, have invented a new, original, and ornamental Design for a Mounting for Fishing Reels, of which the following is a specification, reference being had to the accompanying drawing, forming a part thereof.

I claim:

The ornamental design for a mounting for fishing reels, as shown.

HAROLD F. WILSON.
